UNITED STATES PATENT OFFICE.

KARL BAUMANN, OF URMSTON, ENGLAND, ASSIGNOR, BY MESNE ASSIGNMENTS, TO WESTINGHOUSE GEAR AND DYNAMOMETER COMPANY, A CORPORATION OF PENNSYLVANIA.

DOUBLE-REDUCTION GEAR.

Application filed July 16, 1923, Serial No. 651,778, and in Great Britain July 25, 1922.

This invention relates to double reduction gear of the now well-known floating frame type.

In double reduction gear of this type it has been customary to mount the shafts of the high speed and intermediate gear members in separate floating frames supported from the gear case in such a manner as to admit of limited tilting movement of one shaft relative to another and of any one or more of such shafts relative to the shaft carrying the low speed gear members. With this construction in order to obtain a high degree of efficiency under all conditions of operation a co-planar disposition of the axes of all the shafts is necessary and the main advantage derived therefrom is that the gears are not thrown out of alignment by any distortion of the gear case which may arise, as for instance in the case of a marine installation from distortion or twisting of the ship about a longitudinal axis.

The object of the present invention is to provide a simplified and less costly arrangement of reduction gear of the aforesaid type which will possess the main advantage of the construction set forth above and which will enable a high degree of efficiency to be obtained under all conditions of operation without necessitating a co-planar disposition of the axes of all the shafts. To this end the invention consists in mounting a high speed gear shaft and its associated intermediate shaft so that they can tilt relatively to the low speed shaft but are incapable of tilting movement relative to one another, as for instance by mounting both shafts in a single floating frame. By this means twisting of the gear case will affect neither the engagement of the large gear wheel and the intermediate pinion nor the engagement of the intermediate gear wheel with the high speed pinion.

In order that the invention may be more clearly understood and readily carried into practice reference will now be made to the accompanying drawings in which Fig. 1 is a fragmentary view, in transverse sectional elevation, of one form of structure for supporting the intermediate and high speed shafts of a double reduction gear constructed in accordance with my invention, and Fig. 2 is a similar view of another form of structure for supporting the intermediate

and high speed shafts of a double reduction gear.

In each form illustrated the reduction gear comprises a high speed shaft 3 carrying a first reduction pinion 4 which engages a first reduction gear wheel 5 fast on an intermediate shaft 6 which also carries a second reduction pinion 7 engaging a second reduction gear wheel 8 fast on a slow speed shaft 9 journalled in fixed bearings in the usual manner. The high speed shaft 3 and intermediate shaft 6 are in each case journalled in a common floating frame 10 mounted on I-beams 11 secured to seatings 12 on the gear case 13 and symmetrically disposed relative to the intermediate shaft 6.

With this arrangement it will be apparent that as the shafts 3 and 6 are mounted on a common floating frame 10 they can tilt relative to the shaft 6 but are incapable of tilting movement relative to one another. Consequently any twisting or distortion to which the gear case 13 may be subjected when in service will be compensated by tilting movements of the shafts 3 and 6 relative to the shaft 9. It will also be apparent that as the shafts 3 and 6 are incapable of tilting movement relative to one another the position of the shaft 3 relative to the plane containing the axes of the shafts 6 and 9 is immaterial. In Fig. 1 for instance this shaft is located with its axis in the plane containing the axes of the shafts 6 and 9 while in Fig. 2 it is located a considerable distance away from such plane.

It will of course be understood that the invention is not limited to any particular method of obtaining the tilting or floating movement of the frames 10 or to any particular construction or arrangement of the gear as a whole or of any part thereof other than such as is defined in the succeeding statement of claims.

Having now particularly described and ascertained the nature of my said invention and in what manner the same is to be performed, I declare that what I claim is:

1. In a double reduction gearing embodying a high speed shaft, an intermediate speed shaft and a low speed shaft, a rigid frame member carrying two of said shafts so as to maintain them in parallel relationship, and mounting means for said frame member comprising a section of I-beam having the plane of its web substantially normal

2 to the axis of the third shaft, whereby said frame may tilt with respect to said third shaft by flexure of said web.

- 5 2. In a double reduction gearing embody-
ing a high speed shaft, an intermediate speed
shaft and a low speed shaft, a rigid frame
member carrying two adjacent shafts in the
gear train so as to maintain them in parallel
relationship, and mounting means for said
10 frame member comprising a section of I-
beam having the plane of its web substan-
tially normal to the axis of the third shaft,
whereby said frame may tilt with respect
to said third shaft by flexure of said web.
- 15 3. In a double reduction gearing embody-
ing a high speed shaft, an intermediate speed
shaft and a low speed shaft, a rigid frame
member carrying said high and inter-
mediate shafts so as to maintain them in
20 parallel relationship, and mounting means
for said frame member comprising a section
of I-beam having the plane of its web sub-
stantially normal to the axis of the third
shaft, whereby said frame may tilt with re-
25 spect to said third shaft by flexure of said
web.
4. In a double reduction gear, the combina-
tion of driving, intermediate and driven gear
members, a rigid casing for supporting the
30 driven gear member, a rigid bearing struc-
ture for carrying the intermediate and driv-
ing gear members, and means for flexibly

supporting said bearing structure upon the
casing.

5. In a double reduction gear, the combina-
tion of high, intermediate and low speed
shafts, a rigid casing for supporting the low
speed shaft, a rigid structure for carrying
the intermediate and high speed shafts, and
means for flexibly supporting said structure
upon the casing. 35 40

6. In a double reduction gear, the combina-
tion of a high speed shaft, an intermediate
speed shaft, a low speed shaft, a rigid casing
for supporting the low speed shaft, a single
structure for carrying the intermediate and
high speed shafts, and mounting means for
45 supporting said structure upon the casing,
said mounting means comprising a section
of I-beam having the plane of its web sub-
stantially normal to the axis of the low speed
shaft, whereby said structure may tilt with
50 respect to the low speed shaft by flexure of
the web. 55

7. In a double reduction gear, the combi-
nation of high, intermediate and low speed
shafts, a rigid casing for supporting one of
the shafts, a rigid structure for carrying the
other two shafts, and means for flexibly sup-
porting said structure upon the casing. 60 65

In testimony whereof, I have hereunto sub-
scribed my name this 25th day of June, 1923.

KARL BAUMANN.
